UNITED STATES PATENT OFFICE.

HARRY STEVENS ISHAM, OF BELMAR, NEW JERSEY.

SERVICE-PIPE BOX AND CUT-OFF.

Application filed August 25, 1925. Serial No. 52,426.

This invention relates to service pipe boxes and means for opening and closing the valve of the service pipe, and to those devices known as curb boxes.

5 An object of the present invention is to improve the devices or appurtenances of the character mentioned by simplifying the construction, reducing the number of parts, and obtaining a more thoroughly efficient and 10 effectual device or appurtenance of the character mentioned.

Another object of the invention is to effect 15 a sealing association of the box casings and at the same time to effect an opening of the valve of the service pipe with respect to which the box casings are juxtaposed, and to effect the closing of the valve simultaneously with the disestablishment of the sealing association of the box casings.

20 With the foregoing and other objects in view, the invention resides in the particular provision, relative disposition, and functions of the parts hereinafter fully described and illustrated in the accompanying 25 drawing, in which

Figure 1 is in part a sectional elevation of a service pipe box of the present invention applied to a service pipe and its valve or cut-off.

30 Fig. 2 is in part a sectional elevation of the box removed from the service pipe; the section being taken substantially on the line 2-2 of Fig. 1.

Fig. 3 is a horizontal sectional view taken 35 substantially on the line 3-3 of Fig. 1.

It is the practice to inter service pipes in the ground a sufficient depth to be below the frost line, and that being the case it is necessary to employ a box or casing construction 40 for rendering the valve of the service pipe accessible for opening and closing the valve. To this end there is provided within the present invention an outer box casing 10, which in the present instance, is cylindrical, and an inner box casing 11 which is also 45 preferably cylindrical. The said casings 10 and 11 are adapted to be associated in a manner to be hereinafter explained with a service pipe, such as a service pipe 12 which 50 supplies either water or gas and a valve or cut-off 13 in the pipe 12; one casing fitting within the other and being disposed vertically and in alignment with the valve 13. The lower end of the casing 10 at diametrically 55 opposite points in the wall thereof has cutaways which accommodate the sections of

the pipe 12 which are connected to the valve 13, portions of the wall being extended to provide a flange 15 which rests on the sections of the pipe and which will act as a holding means when the casing 10 is sunk. The upper end of the casing 11 is provided with a cap 16 which closes the upper end of the casing 11 and which provides a marginal portion 17 having a depending flange 18; there being a space 19 between the flange and the wall of the casing for the reception of one or more gaskets 20.

The casing 10 and 11, in the present embodiment of the invention, embody or have 70 associated therewith means for causing the inner casing 11 to move longitudinally relatively to the outer casing 10 to cause the marginal portion 17 and the flange 18 to engage the upper end of the casing 10, and 75 the said means consists of pins 21 which extend radially inward from the wall of the casing 10 diametrically opposite each other, whereas, the lower end of the casing 11 is provided with substantially L-shaped slots 80 22 which occur in the wall of the casing diametrically opposite each other. Each of the slots 22 being L-shaped provides a branch 23 and a branch 24, the walls of the latter being inclined upwardly from the 85 branch 23 to act as a cam when the pins 21 respectively are in the branches 24 and the casing 11 is turned, which will cause the closing engagement of the cover portions with the upper end of the casing 10. 90

In order that the valve 13 will be opened when the cover portions are brought into sealing or closing relationship with the upper end of the casing 10, and to close the valve 13 when the cover portions are 95 disengaged from the upper end of the casing 10, there are provided pairs of spaced lugs 25 at diametrically opposite points on the wall of the casing 11. The lugs 25 of each pair are arranged respectively at opposite sides of the branch 23 of the particular slot 22. It is to be noted that the end wall of the branch 24 of each slot 22 is at a point substantially 90° from the point at which the branches 23 respectively open 100 through the lower end of the casing 11. The arrangement is such that when the pins 21 are in the ends respectively of the branches 24 as shown in Fig. 1 the cover portions 17 and 18 will be down in sealing 105 relationship with the upper end of the casing 10 and the handle 26 of the plug 27.

of the valve 13 will be disposed substantially in a plane at a right angle with respect to a vertical plane through the pins 21. From the foregoing it will be apparent that the present invention contemplates the insurance of a closed valve when the cap 16 is removed from sealing relation with the upper end of the casing 10, and an opened valve when the cap 16 is in sealing relation with the upper end of said casing 10. Any suitable type of valve construction may be employed so long as the cut-off or plug of the valve is provided with a handle or means similar to the handle 26. Portions of the handle 26 are received respectively between the pairs of lugs 25 as shown most clearly in Figs. 1 and 3 and by turning the casing 11 substantially 90° the cap 16 will be closed upon the upper end of the casing 10 and the valve will be opened. When the pins are disposed against the walls of the branches 24 respectively, further turning movement of the casing 11 in one direction is prevented, although it may not be necessary to turn the casing 11 the full 90° to effect the closing of the cap on the upper end of the casing 10. In the drawing the plug 27 of the valve is shown as being provided with a pin 28 which is adapted to engage shoulders 29 on the valve casing, the said shoulders being substantially 90° apart to limit the movement of the plug in opposite directions. When the pin 28 is in engagement with one of the shoulders 29 the valve is open and when the pin 28 is in engagement with the other shoulder 29 the valve is closed. In order to permit the casing 11 to be turned and to prevent the same from being withdrawn from the casing 10, there is provided in the casing 11 an annular groove 30 in which is disposed the end of a screw 31. The groove 30 is sufficiently wide to permit the relative longitudinal movement of the casing 11 with respect to the casing 10.

It is to be understood that the invention is not restricted to the precise arrangement of parts shown and described, as details of construction may be modified and re-arranged without departing from the spirit of the invention, the scope of which is limited only by the terms of the appended claims.

I claim:

1. The combination with a service pipe valve, of an inner and an outer box casing, a

cap on the inner casing adapted to close down on the outer casing, coacting means on the casings and valve which serve to open the valve and simultaneously close the cap down on said outer casing when a force is applied to said inner casing. 60

2. In a service pipe box, an inner casing, an outer casing, a cap on the inner casing which is adapted to be closed down on the upper end of said outer casing, coacting means on said casings which cause the cap to close down on the upper end of said outer casing when a turning force is applied to said inner casing, and means for permitting the turning of the inner casing and for preventing the withdrawal of said inner casing from the outer casing. 65 70

3. The combination with a service pipe valve whose plug is provided with a handle disposed diametrically with respect to the axis on which the plug turns in opening and closing the valve, of an outer casing, an inner casing, a cover closing the upper end of said inner casing and having a marginal portion and flange which are adapted to accommodate the upper end of the outer casing, pins extending radially inward from the said outer casing diametrically opposite each other, cams on said inner casing which coact with said pins when the inner casing is turned to cause the cover, marginal portion and flange to bear down in sealing relationship with the upper end of said outer casing, and diametrically opposed pairs of spaced lugs on said inner casing which accommodate portions of said handle to cause the plug of the valve to turn to open the valve when said inner casing is turned. 75 80 85 90 95

4. The combination with a service pipe valve, of a box casing, a cap adapted to be brought into sealing relationship with the upper end of said box casing, coacting means carried by said cap and said valve respectively which serves to open the valve and simultaneously bring the cap down in sealing relationship with the upper end of said box casing when said cap is turned in one direction, said coacting means also serving to close said valve and simultaneously remove said cap from its sealing relationship with said upper end of said box casing when said cap is turned in a direction opposite to that first mentioned, and means which limits the turning movement of said cap in either direction. 100 105 110
